(57) **CLAIM**

The ornamental design for a wheeled measuring device, as shown and described.

DESCRIPTION

FIG. 1 is a top and side perspective view of our design for a wheeled measuring device;

FIG. 2 is an elevation view thereof from the same side as in FIG. 1;

FIG. 3 is an elevation view thereof from the side opposite that in FIGS. 1 and 2;

FIG. 4 is a front elevation view thereof;

FIG. 5 is a rear elevation view thereof;

FIG. 6 is a plan view thereof; and,

FIG. 7 is a bottom view thereof.

The portions of the wheeled measuring device shown in dotted lines do not constitute a part of the claimed design.
